UNITED STATES PATENT OFFICE.

SUMPTER LEA HARWOOD, OF FAUNSDALE, ALABAMA, ASSIGNOR OF ONE-HALF TO JOHN H. MINGE, OF SAME PLACE.

BORING-MACHINE.

SPECIFICATION forming part of Letters Patent No. 674,699, dated May 21, 1901.

Application filed June 27, 1900. Serial No. 21,786. (No model.)

To all whom it may concern:

Be it known that I, SUMPTER LEA HARWOOD, a citizen of the United States, and a resident of Faunsdale, in the county of Marengo and State of Alabama, have invented a new and Improved Boring-Machine, of which the following is a full, clear, and exact description.

The invention relates to well-boring machines in which water is forced to the revolving drilling-tool to assist in loosening the ground and to cause the loose material to flow up in the drill-hole in the space between the wall of the drill and the drill-hole.

15 The object of the invention is to provide a new and improved well-boring machine which is simple and durable in construction and arranged to allow of regulating the rate of cutting according to the nature of the soil 20 without subjecting the drill to the weight of the pipe-line and at the same time preventing the pipe-line and drilling-tool from dropping into and being lost in a bed of quicksand, if such is encountered.

25 The invention consists of novel features and parts and combinations of the same, as will be fully described hereinafter and then pointed out in the claims.

A practical embodiment of the invention 30 is represented in the accompanying drawings, forming a part of this specification, in which similar characters of reference indicate corresponding parts in all the views.

Figure 1 is a side elevation of the improvement with parts in section. Fig. 2 is a sectional plan view of the same on the line 2 2 in Fig. 1. Fig. 3 is a plan view of one of the feed devices. Fig. 4 is an enlarged sectional plan view of the improvement on the line 4 4 in Fig. 1. Fig. 5 is an enlarged sectional side elevation of the water-inlet, and Fig. 6 is a side elevation of a modified form of the feed cross-head with parts in section.

The improved well-boring machine is provided with a hollow drill-rod A, connected at its upper end with a water-supply B and supporting at its lower end a drilling-tool C for cutting the material and assisted by the water passing through the drill-rod A and issuing in close proximity to the drill-tool C, preferably at opposite sides thereof. The

drill-rod A extends loosely through a hollow shaft D, mounted to turn at its upper end in a bearing E, carried by an overhead frame structure F, and on the lower end of said hollow shaft D is secured a bevel gear-wheel G, the lower end of the hub of which is mounted on a ball-bearing step E', carried by the main frame F', located over the drill-hole and on adjacent ground, as is plainly indicated in the drawings. The bevel gear-wheel G is in mesh with a pinion G', mounted loosely on a shaft H, carrying a pulley H', connected by belt with other machinery for imparting a rotary motion to the said shaft. A clutch 60 I is mounted to turn with and to slide on the shaft H and is adapted to engage a corresponding clutch member G² on the hub of the pinion G'. The clutch I is engaged by a lever I' under control of the operator to 70 throw the clutch in or out of mesh with the member G², so as to rotate the pinion G' from the shaft H whenever desired. When the pinion G' is rotated, a rotary motion is given to the bevel gear-wheel G, and consequently 75 to the shaft D, and the rotary motion of the latter is transmitted to the drill-rod A by means of a cross-head J, secured on said drill-rod A by set-screws J'. The cross-head J is provided with side arms J², which extend 80 through vertically-disposed slots D' in the shaft D, so that when the shaft D is rotated the arms J², and with them the cross-head J, are turned around to rotate the rod A, and at the same time the cross-head J is free to slide 85 down and up in the shaft D for lowering the drill-rod A and for feeding the drilling-tool C downward into the material in the bottom of the well-hole.

In order to feed the cross-head J, and with 90 it the rod A, downward, the arms J² are provided with nuts J³, in which screw feed-screws K K' are secured ratchet-wheels N, engaged by pawls N', pivoted on spring-pressed levers N², fulcrumed loosely on the feed-screws and adapted to engage a fixed 100 arm O on the overhead framework F, so that when the cross-head J is turned around by

the rotation of the shaft D then the said levers N² are successively moved in contact with said fixed arm O to receive a swinging motion for imparting an intermittent rotary motion to the ratchet-wheels, and consequently to the feed-screws K K', so as to move the cross-head J downward. The levers N² on leaving the fixed arm O return to a normal position by the action of their springs.

10 In order to turn the two feed-screws K K' in unison when one receives a rotary motion by the ratchet-wheel and pawl mechanism above described, the following device is provided: On the lower ends of the feed-screws K K' are secured pinions P P', respectively in mesh with a gear-wheel P², mounted to rotate loosely on the shaft D, so that when one feed-screw K or K' is turned the said gear-wheels P P² P' impart a rotary motion to the 15 feed-screws, so that both turn in unison and properly feed the cross-head J in a downward direction.

15 In order to move the cross-head J back into an uppermost position for a new or second downward feeding of the drill-rod A, it is necessary first to move the clutch I out of mesh with the clutch member G², and then the feed-screws K K' are turned in an opposite direction by hand, and for this purpose 20 one of the feed-screws is provided with a bevel gear-wheel Q, in mesh with a bevel gear-wheel Q', mounted to turn on a stud projecting from the bearing L', and the hub Q² of the bevel gear-wheel Q' is adapted to be engaged by a crank-arm Q³ under control of the operator. When the operator turns the crank-arm, a rotary motion is given by the gear-wheels Q Q' to the feed-screw K, and the other feed-screw K' is simultaneously rotated 25 40 owing to the gear-wheels P P² P' and feeding-screws K K' being turned in an opposite direction to cause a return or upward movement of the cross-head J at the time the set-screws J' are loosened, so that the cross-head 45 slides back on the drill-rod A without moving the same upward. When the uppermost position is reached, the set-screws J' are again screwed up to again fasten the cross-head J to the drill-rod A, after which the operator 50 throws the clutch I again in mesh with the clutch member G², so that the shaft D is again rotated for turning the tool C and for automatically feeding the same downward by the mechanism above described.

55 The water-inlet B, previously mentioned, consists, essentially, of a stuffing-box B', in which is mounted to turn a short pipe B², formed at its inner end with a collar B³ and at its outer upper end with an eye B⁴ for connection with the hoisting mechanism for raising the drill-rod A whenever desired. From the upper outer end of the pipe B² also extends a branch pipe B⁵, connected by a hose B⁶ with water under pressure. It is evident 60 65 that when the rod A is rotated the pipe B² will remain stationary, as it is mounted to turn in the stuffing-box B', and consequently

entanglement of the hose B⁶ is not liable to take place.

The hoisting mechanism referred to is also actuated from the shaft H, and for this purpose the said shaft is provided with a second clutch I², similar to the clutch I and under control of the operator by a lever I³. (See Fig. 2.) The clutch I² is adapted to be thrown in mesh with a clutch member H² on a bevel-pinion H³, mounted to rotate loosely on the shaft H, and this bevel-pinion H³ is in mesh with a gear-wheel H⁴, secured on the shaft H⁶, carrying the hoisting-drum H⁶, on which winds a hoisting-rope adapted to be connected with the eye B⁴, previously referred to. The hoisting-drum H⁶ is also provided with a suitable brake mechanism H⁷ under control of the operator.

85 In the modified form (shown in Fig. 6) the arms J² of the cross-head J are provided with bearings J⁴ for nuts J⁵ to slide in vertically, the nuts being engaged by the feed-screws K K' for feeding the cross-head J and the rod A downward, as previously described. Each nut J⁵ is provided at its lower end with a collar S⁶, adapted to rest on the corresponding bearing J⁴, and said nuts are held from turning in the bearings by screws J⁷, extending through vertical slots in the said bearings, to allow the nuts to move downward in the bearings should the feed be too rapid for the action of the drilling-tool C, the arrangement enabling the operator to adjust the feed and prevent too much weight from coming upon the drill. It is understood that the arrangement described does not force the drilling-tool C downward, but rather assures a constant pressure on the drilling-tool. Should the automatic feed be 100 too rapid, the operator will at once notice this by the nuts J⁵ leaving their seats, and hence can readily adjust the feed to conform to the rate of cut. When a hard rock is encountered, the nuts may be run to the bottom of the slot and the ratchets thrown out of gear, and by winding the rope around the drum and slackening alternately the drill-rod may be given a rapid reciprocating motion at the same time that the rotary motion is being 115 imparted. This may be done without undue friction, as with other machines of the rotary type.

Having thus fully described my invention, I claim as new and desire to secure by Letters 120 Patent—

1. A boring-machine, comprising a revolvable hollow shaft, a hollow drill-rod extending through said shaft and connected at its upper end with a water-supply, and provided at its lower end with a drilling-tool, a cross-head secured on the said drill-rod and extending through a slot in the said shaft, so that the rotation of the latter rotates the drill-rod by said cross-head, and a feed-screw for said cross-head and carried bodily around with the same and receiving a turning motion during such bodily movement, substantially as shown and described.

2. A boring-machine, having a feed for a revolving hollow drill-rod, and comprising a feed-screw, a cross-head secured on the drill-rod and in which screws the said feed-screw 5 to feed the cross-head and drill-rod, means for turning the cross-head, and means for intermittently turning the screw-rod during each revolution of the cross-head carrying the screw-rod bodily around, substantially as 10 shown and described.
3. A boring-machine, having a feed for a revolving hollow drill-rod, and comprising a feed-screw, a cross-head secured on the drill-rod and in which screws the said feed-screw 15 to feed the cross-head and drill-rod, means for turning the cross-head, and means for intermittently turning the screw-rod during each revolution of the cross-head carrying the screw-rod bodily around, a ratchet-wheel on the said 20 screw-rod, a pawl engaging said ratchet-wheel, a lever carrying the pawl, and a fixed part adapted to be engaged by the said lever, to impart a swinging motion to the latter and turn the ratchet-wheel and feed-screw, substantially as shown and described. 25
4. A boring-machine, comprising a revolvable hollow shaft, a drill-rod extending through the shaft, a cross-head secured on said drill-rod and revolving with said shaft and mounted 30 to slide thereon, feed-screws screwing in nuts on the cross-head and arranged outside of said shaft, bearings for the screw-rods to turn in and carried by said shaft, means for intermittently turning the screw-rods, and a 35 gearing for connecting the screw-rods with each other and simultaneously turning the same when one receives a turning motion, substantially as shown and described.
5. A boring-machine, having a revolvable 40 drill-rod, means for rotating the same, and feeding mechanism therefor, comprising a cross-head secured to the drill-rod, a feed-screw engaged with a threaded part of the cross-head and carried to move bodily around 45 the axis of the drill-rod, a ratchet-wheel fastened to the feed-screw, a pawl engaging the ratchet-wheel, a lever fulcrumed on the feed-screw and carrying the pawl to actuate the ratchet-wheel, and a fixed member adapted 50 to be engaged by the lever as it moves with

the feed-screw, whereby to turn the feed-screw independently of its movement around the drill-rod.

6. In a boring-machine, the combination of a revolvable drill-rod, a cross-head attached to the drill-rod, a longitudinally-slotted sleeve or hollow shaft inclosing the drill-rod and having the cross-head projected through the slots therein, means for rotating the hollow shaft to drive the drill-rod through the medium of the cross-head, a feed-screw supported on the hollow shaft and moving with the hollow shaft bodily around the axis thereof, a nut on the cross-head, the said nut working with the feed-screw, and means for rotating the feed-screw independently of its movement with the hollow shaft. 60

7. In a drilling-machine, the combination of a revolvable drill-rod, a hollow shaft or sleeve inclosing the drill-rod and mounted to turn, the hollow shaft being formed with a longitudinally-extending slot, a cross-head fastened to the drill-rod and extending through the slot in the hollow shaft, whereby to drive the cross-head from the hollow shaft, a feed device 70 engaging the cross-head to feed the drill-rod, such feed device being carried by the hollow shaft and turning bodily with the same around its axis, and means for imparting to the feed device movement independently of 80 the movement of the hollow shaft, whereby to drive the feed device to feed the drill-rod.

8. A boring-machine having a revolvable drill-rod and means for rotating the same, and a feed mechanism for the drill-rod comprising a cross-head fastened on the drill-rod, a feed-screw mounted to turn with the drill-rod bodily around the same, the feed-screw being independently revolvable and being engaged with a threaded part on the cross-head to feed 90 the drill-rod, and means for imparting an independent rotary movement to the feed-screw. 85

In testimony whereof I have signed my name to this specification in the presence of 95 two subscribing witnesses.
